DISPLAY RACK

John C. Pappas, Jr., Belmont, Mass., assignor to
C. Pappas Company, Inc., Boston, Mass.

Filed Apr. 10, 1970, Ser. No. 22,368

Term of patent 14 years

Int. Cl. D6—06

U.S. Cl. 80—10

FIG. 1 is an elevation view of the display rack showing the new design;

FIG. 2 is a top plan view thereof; and

FIG. 3 is a bottom plan view thereof.

The broken line representation of an advertising card in FIG. 1 is for purposes of illustration only.

I claim:

The ornamental design for a display rack, as shown and described.
